Inventor:

James Chenoweth

United States Patent Office.

JAMES CHENOWETH, OF SHELBYVILLE, MISSOURI.

Letters Patent No. 101,710, dated April 12, 1870.

IMPROVEMENT IN ROTARY SPADERS.

The Schedule referred to in these Letters Patent and making part of the same.

To all whom it may concern:

Be it known that I, JAMES CHENOWETH, of Shelbyville, in the county of Shelby and State of Missouri, have invented certain new and useful Improvements in Rotary Spaders; and I do hereby declare the following to be a full and exact description of the same, reference being had to the accompanying drawings, in which—

Figure 1 is a side elevation of the spader complete.

Figure 2 is a plan view of the same.

Figures 3, 4, and 5 are detail sectional views of parts, hereinafter more fully described.

The object of this invention is to provide a machine which, in traversing the soil, will raise and turn over the same; and

It consists in the provision of one or more traction-wheels, provided with spades, automatically operated by means hereinafter fully specified.

I have illustrated two traction-wheels, provided with spades, but it is obvious that I may employ a lesser or greater number, and that the spirit of my invention will be preserved, although but one or any larger number is employed.

A represents the frame;

B, the tongue;

C, a revolving colter; and

D, a bearing wheel.

E represents the traction-wheel, which is firmly secured to the axle E', journaled in the frame A.

F represents a cam, shown in perspective in fig. 5, which is firmly secured to the frame A.

G represents shovels, secured by ball and socket-joint to the axle E', as seen at G', and whose handles pass through openings in the periphery of the wheel E, and through apertures in the slide G", which moves laterally in guides or ways on the inside of the periphery of said wheel.

The slide G" is provided on that end next the cam with two studs g', which fit, one on each side of the rim F' of the cam F.

As the wheel E revolves, the studs g' pass entirely around the cam, and retain the slide securely in the one position until the shovels leave the ground, when, owing to the departure which the cam takes at this point from a straight concentric line, the slide G" is pushed over toward the other side of the wheel, and the shovels, consequently, caused to revolve a quarter of a circle, and discharge their load.

The revolution of the shovel-handle being caused by the pin c, in the shovel-handle, coming in contact with the shoulder d on the wheel, as clearly shown by dotted lines in fig. 4.

At this point the cam curves back to the line originally taken, and the shovels are automatically returned to condition for entering the soil.

When more than one wheel is used, I employ two distinct frames, united by a rod at the front, so that each frame may adapt itself to the inequalities of the surface without interfering with the operation of the other.

I also make one frame longer than the other, as clearly shown in fig. 2, whereby the soil discharged by the second wheel is thrown in the rear of the first, and not against it, as would be the case were the two wheels in a line and upon the same axle.

What I claim as my improvement, and desire to secure by Letters Patent, is—

1. The wheel E, spades G, ball and socket-joint G', and slide G", when combined and arranged as specified.

2. In combination with the wheels E and spades G, the rotating colters C, as specified.

3. In combination with the elements of the first claim, the cam F, when operating as and for the purpose specified.

JAMES CHENOWETH.
